FLUID HEATER CONTROL APPARATUS

Russell F. Dotson, Kankakee, Ill.

Application January 15, 1951; Serial No. 206,028

8 Claims. (Cl. 236—21)

1

This invention relates to fluid heater control apparatus and is particularly well adapted for gas fired installations. The invention relates to apparatus of the same general type as that disclosed in an application of the same inventor, Serial No. 131,473, filed December 6, 1949 which has matured into Patent No. 2,628,033, of which this application constitutes a continuation-in-part.

As set forth in the earlier application, apparatus of the type here involved usually comprises a main burner and a pilot burner, and it is of fundamental importance that no fuel be supplied to the main burner while an attendant is lighting the pilot burner. In this case as in the earlier one, the main burner valve is controlled by bleeding fuel from one side of a diaphragm more rapidly than it is replaced from the fuel source, as result of which, the control of the bleed fuel will determine the opening and closing operations of the main burner valve. Accordingly, an arrangement has been provided herein to prevent kindling of the pilot burner at the time that gas can be bled from behind the diaphragm and at the same time reopening of the bleed passage is prevented until after such time that the pilot burner fuel primer has been removed from its pilot valve opening position. In the present case the operator performing these functions of priming and obstructing the bleed passage, is preferably a single member performing the two functions.

When the fluid being heated has reached a temperature exceeding a predetermined safe value, the flow of both bleed and pilot fuel will be interrupted, requiring manual priming to re-establish the flow of fuel to either the main or pilot burner.

A thermocouple exposed to the pilot burner flame supplies current to an electromagnet at a value sufficient to maintain a valve in its open position but insufficient of itself to open the valve from a closed position; hence, a manual primer is provided to initiate the opening of this valve, whereupon the pilot burner can be started and the resulting thermocouple current will then hold the valve in its open position. In order to keep the current requirements of the thermocouple circuit at a minimum consistent with dependable operation, the form of the valve and its seat become significant. It has been found that when the valve is assigned the form of a paramagnetic ball, a smaller force is required to hold it elevated in contact with an inclined plane than would be necessary were the mag-

2

netizing force required to suspend the ball fully against the force of gravity out of contact with such an inclined surface. Accordingly, a well has been provided to receive such a ball, the axis of the well being inclined to both the horizontal and vertical. Such an arrangement has raised another problem however, which has been solved in accordance with the present invention, namely that of assuring proper seating of the valve in its closed position. This is accomplished by having the valve port at the bottom of the well defined by a relatively sharp edge to provide a line contact with the ball, and the edge is spaced from the longitudinal wall or walls of the well by a small distance which will always be less than the radius of the ball.

When the temperature of the fluid being heated drops below a preset value, a thermo-sensitive element responds to permit the flow of bleed gas, and similarly, when the fluid temperature achieves a predetermined elevated value, the element closes a valve in the bleed gas line. A preferred type of actuator for this purpose assumes the form of a permanent magnet influencing a paramagnetic valve, the magnet being attached to a thermally actuated arm which travels in an arcuate path to transmit small movements of a remote thermo-sensitive element, accompanied by a magnification of such movements, to a control element which in turn controls the fuel supply. The transmitting member traveling in such an arcuate path will assume the form of a pendulum in a preferred embodiment of this invention, the free end of which carries a permanent magnet for cooperation with the valve or valves under its influence. When the safe upper temperature has been exceeded, the permanent magnet assumes a position in which its flux opposes that of the thermocouple supplied electromagnet to an extent sufficient to at least partially neutralize the effect of the electromagnet causing the valve to close and interrupt the flow of both pilot and bleed gas.

The thermo-sensitive element is preferably of the surface contact type, and provision has been made to prevent damage to the system because of excessively low temperatures to which it may be subjected, and furthermore, in conjunction with the adjusting means for presetting the desired temperatures, a safety feature has been incorporated to avoid excessive heating even though such adjusting member might become damaged or separated from the assembly.

Among its many aspects, the present invention contemplates fluid heater control apparatus

comprising a valve casing, a diaphragm dividing the casing into two chambers, fuel inlet and outlet tubes having ports communicating with the first of the chambers, a valve connected with the diaphragm for registry with one of the ports, means interconnected with one of the tubes defining a pilot fuel passage, means defining a bleed fuel passage communicating with the second of the chambers for controlling the diaphragm and valve, a control valve interposed in the pilot fuel passage, and an operator movable to a position opening the control valve and closing the bleed fuel passage. The operator is preferably provided with means for biasing it towards a position opening the bleed fuel passage, which may assume the form of a coil spring.

The apparatus preferably comprises a selecting valve carried by the casing interposed between the fuel inlet tube on the one hand and the first chamber and passages on the other, for selectively supplying fuel to either the first chamber or passages or both. The valve may be of the rotary type having two interconnected ports in communication with the fluid inlet tube, for distribution of fuel to the pilot fuel and bleed fuel passages only, or to these passages and the first chamber jointly. The valve also has a position in which there will be no passage of fluid from the fuel inlet tube to either the first chamber or the passages.

The invention also contemplates means defining a reduced passage extending and converging from the first chamber to the outlet port, the diaphragm connected valve being received in this passage for registry with the outlet port. The cross-section of the passage adjacent the outlet port preferably approximates that of the valve so that as the valve approaches its seat there is a progressively increasing biasing effect, due to fuel flow, tending to close the valve.

A more complete understanding of the invention will follow from a detailed description of the attached drawings wherein:

Fig. 1 is a side elevation, partially in section, depicting a form of the invention applied to a domestic gas water heater;

Fig. 2 is a front elevation, on a somewhat larger scale, of the control apparatus of Fig. 1;

Fig. 3 is a sectional elevation on a further enlarged scale taken along line 3—3 of Fig. 2;

Fig. 4 is a fragmentary sectional elevation, on an enlarged scale, taken along line 4—4 of Fig. 2;

Fig. 5 is a fragmentary sectional view taken along line 5—5 of Fig. 4, having a pilot fuel adjusting valve superimposed thereon to indicate its function;

Fig. 6 is a fragmentary sectional elevation taken along line 6—6 of Fig. 2;

Fig. 7 is a fragmentary sectional view taken along line 7—7 of Fig. 6;

Fig. 8 is a fragmentary sectional elevation taken along line 8—8 of Fig. 3;

Fig. 9 is a fragmentary sectional elevation taken along line 9—9 of Fig. 8;

Fig. 10 is a fragmentary elevation, partially broken away to illustrate the selecting valve;

Fig. 11 is an exploded perspective view showing the valve and its associated elements; and

Fig. 12 is a fragmentary section taken along line 12—12 of Fig. 10.

The invention has been depicted as applied to a domestic hot water heater in Fig. 1 of the drawings, wherein a storage tank 10 is provided with a head 12, a bottom 14, a skirt 16, and a

pan 18, enclosing a firebox 20 which receives a main burner 22 provided with the usual bottle mixer 24. Suitable brackets 26 support the main burner above the pan in a position to receive an orifice spud 28 provided with an orifice 30, Fig. 3. The orifice spud is secured to a portion of the skirt or a mounting plate 32 between an adjustable nut 34 and a flange 36 carried by the spud. The orifice spud is threaded into a valve casing 38, the reduced end 39 of the spud defining a valve seat for a flexible body or disk 40 which is carried by a diaphragm 44 for movement in a convergent passage 46 to and from its closed position depicted in Fig. 3 of the drawings. The disk is supported by a rigid backing washer 41 carried by a stem 42 suitably secured thereto and to the diaphragm.

The diaphragm 44 is clamped between the casing 38 and a cover plate 48 suitably secured together by fastening means 50 such as rivets or screws. The diaphragm and its valve 40 are biased towards the valve seat by means of a spring 51 interposed between the diaphragm and the cover 48.

A thermal control housing 52 is mounted on the upper portion of the valve casing, and is provided with a head 54 secured thereto by means of a screw 56 and containing a spirally wound thermo-sensitive bimetallic element 58 which is presented towards the surface whose temperature is to be controlled through an open side 60. A control knob 62 provided with limiting stops 64 and 66 is employed to adjust the thermo-sensitive element where higher or lower temperatures are desired. As indicated in Fig. 2 of the drawings, when the knob 62 is moved to its extreme position in a counterclockwise direction, the high heating condition is permitted. On the other hand, if the maximum temperature is to be the lowest for which the system is designed, the knob will be turned to its extreme clockwise position.

Fuel is supplied to the casing 38 through a tube 68 threaded into the lower portion thereof, and through a selecting or distributing valve 70 into the chamber 72 defined on the right side of the diaphragm 44 as viewed in Fig. 3. With the valve 42 closed as shown in Fig. 3, there can be no passage of gas through the main burner 50 supply port 74, but depending upon the position of the selecting valve 70, gas might flow through a passage 76 formed on the periphery of the valve 70 and pass through a filter supply passage 78 into the filter chamber 80, passing upwardly therethrough, and through suitable filtering material 82 to a pilot fuel port 84 and a bleed fuel supply port 86. The upper end of the filter chamber is closed by a plug 88 threaded therein as clearly shown in Fig. 4. Fuel entering the pilot supply port 84 travels through a pilot fuel passage 90, at an intermediate point of which it encounters a pilot adjusting valve 92 in the form of a screw containing a fixed orifice 94 serving as the upper limit for the amount of fuel that can be delivered to the pilot under normal operating conditions. From this point, the pilot fuel passage extends into the chamber 96 of the ball valve 98 which serves to cut off both pilot fuel and bleed fuel under emergency conditions. Under normal operating conditions, the ball 98 will be elevated above its seat 100, in a manner to be described, permitting fuel from the pilot gas passage 90 to enter the pilot gas delivery passage 102 connected by means of a fitting 104 with a pilot tube 106 whose tip 108

receives a position adjacent the main burner as depicted in Fig. 1. Fuel entering the port 88 moves through a bleed supply passage 110, emerging at the face of the casing member 38 in registry with an opening 112 formed through the marginal portion of the diaphragm 44. This opening registers with a short axial passage 114 formed through the adjacent face of the cover plate 48 which intersects a radial passage 116 extending from the chamber 118 formed on the left side of the diaphragm as viewed in Fig. 3, into a ball chamber 120 also formed in the cover member and accessible through a threaded opening customarily closed by a plug 121. This ball chamber is intersected by a substantially axial passage 122 which registers with a port 124 formed through the diaphragm 44 and with a passage 126 extending through the casing 38 towards the well or ball chamber 96. The bleed fuel passage 125 intersects a passage 128 through which an operator or primer rod 130 projects to serve both the function of elevating the ball 98 from its seat 100 and controlling the passage of fuel between the bleed gas passage 126 and the well or ball chamber 96. The primer rod 130 carries a head or push button 132 biased towards its retracted position by a spring 134 having one end seated on a shoulder 138 provided by the casing 38. In its retracted position, the button 132 bears against a portion of the flange of the cover plate 48. It will be clear that when the button 132 is depressed, the end of the primer rod 130 will be projected to lift the ball 98 and at the same time close the bleed gas passage 126. When the button is released, the spring 134 biases the primer rod to its outer or retracted position depicted in Fig. 7, under which conditions there is no interference with movement of the ball 98, and the bleed passage 126 is opened.

When the primer 130 is advanced by depressing the button 132, the ball 98 will be elevated and retained in its valve opening position in contact with the core 144 of an electromagnet 146 having a winding 146 whose leads are connected through a conduit 148 with a thermocouple 150 located adjacent to the pilot tip 108. Assuming that the pilot is burning, and has sufficiently heated the thermocouple, the electromagnet 146 will maintain the ball 98 suspended and fuel can continue to flow to the pilot burner. The axis of the ball chamber, which is coincident with the line 6-8 of Fig. 2, is inclined with respect to both the horizontal and vertical when the control apparatus is in its intended operating position. It has been found that by so inclining the wall of the ball chamber, a smaller force will be required to maintain the ball elevated above its seat. However, to assure proper seating of the ball when it has been released, the seat 100 having a rather sharp configuration to provide a line contact for the ball cooperates with a shoulder 152 spacing the edge of the seat from the wall of the chamber a radial distance smaller than the radius of the ball itself.

When it is desired to place the apparatus into operation, the button 132 of primer rod 130 will be depressed and held in that position long enough to light the pilot 108 and heat the thermocouple 150. This can occur however, only if the peripheral passage 76 of the valve 70 is in registry with the filter supply passage 78. As depicted in the drawings, the valve 70 is in its "on" position providing communication from the inlet tube 68 into the valve chamber 154, through the internal passage 156 extending axially of the 75

valve plug, through the radial passage 158 penetrating the frusto-conical wall of the plug, to the chamber 72 through a passage 160 provided in the casing, and to the filter supply passage 78 through the passage 76 formed on the periphery of the plug and extending circumferentially thereof through an arc of approximately 90°. A spindle 162 carrying the valve plug projects beyond the casing through a retaining plate 163 secured to the casing by four screws 164, one of which has an elongated head 165 to serve as a limiting stop. After the plug has been inserted into its complementary bore 166 formed in the casing, a helical biasing spring 167 is slipped over the stem and the retaining plate 163 having an opening 168 to receive the spindle is applied by means of the screws 164. A control knob 169 has a central opening 170 through which the stem is passed until a pin 171 can be introduced through its transverse opening 172, whereupon the knob will be retracted until the pin becomes seated in its diametrically disposed slots 173. This relationship of the pin and slots is maintained by means of a combined index and cover plate 174 which has a lobe 175 covering the opening 170 of the knob. The plate 174 is adjustably secured to the knob 169 by means of a pair of screws 176 projecting through an arcuate slot 177 into threaded engagement with openings 178 provided in an arcuate segment 179 received in an annular groove 180 formed in the rear surface of the knob. In assembled relationship, the elongated head 165 rides in the groove 180 in the path of the segment 179 limiting rotation of the knob in both directions. One of the limiting positions corresponds with the "On" designation carried by the bent end of the index plate. The other limiting position is indicated by the "Off" designation carried by the knob and an intermediate position is marked "Pilot" on the knob. These markings are related to an arrow 181 provided on the casing so that an attendant will immediately know the condition of the valve. When the knob 169 is turned clockwise from the position shown until the "Pilot" position is attained, the passage 158 moves out of registry with respect to the passage 160, cutting off the supply of fuel to the main chamber 72, yet the peripheral passage 76 still registers with the filter passage 78 permitting the pilot and bleed fuel to continue to flow. Further clockwise rotation of the knob however, to the "Off" position will cut off the pilot and bleed fuel as well.

The ball chamber 120 receives a ball 182 which is held in its elevated position as depicted in Fig. 3 to permit the passage of bleed gas, and thereby permit opening of the main burner valve, by means of a permanent magnet 184 carried by a pendulum-like member 186 whose upper end is secured to the free end 188 of the thermo-sensitive bimetallic member 53. In the position shown in Fig. 3, the temperature to be controlled by the thermo-sensitive element 53 has not reached the maximum value and accordingly, the permanent magnet 184 is positioned closely enough to the ball 182 to elevate it and maintain the bleed gas passage open. As the temperature desired within the tank 10 is reached, the permanent magnet 184 will be moved towards the right as viewed in Fig. 3 and ultimately, its elevating force upon the ball will be diminished to a point where the ball will drop and close the bleed gas passage. If for any reason, temperature of the material to be controlled should continue to rise, the permanent magnet 184 will continue to travel to-

wards the right until it approaches the ball chamber 96, and if the temperature is sufficiently high, the influence of the permanent magnet 184 will at least partially neutralize the effect of the electromagnet 146 so that the ball 98 will drop and shut off both the bleed fuel and pilot fuel. When the passage of bleed fuel has been terminated, as will be evident to those skilled in the art, the fuel pressure on opposite sides of the main diaphragm 44 will become equal and the burner valve will close. If operation of the apparatus is to be restored, it will be necessary to prime the apparatus manually under which conditions, the main burner will remain inoperative and there will be no flow of bleed fuel until the primer 130 has been retracted.

The inner end of the thermo-sensitive element 58 is secured to a shaft 190 which is rotatably supported in suitable bearings provided by the head 54. The shaft 190 may be retained against axial movement by means of one or more suitable screws 192 threaded into the casing or head 54. The shaft 190 is provided with a transverse bore through which a pin or screw 194 is threaded, the head 196 of the screw cooperating with an abutment 198 whose position can be adjusted by manipulation of the screw 200 on which it is carried. The screw 200 is threaded in a boss 202 provided by the head 54, and externally, carries a lock nut 204 to secure the knob 62 in an adjusted position. As the temperature to be controlled increases, the head 196 of the screw will move towards the abutment 198, at which point further deformation of the thermo-sensitive element 58 will be reflected in movement of its free end 188 and consequently, the permanent magnet 184. As the temperature drops below the value for which the control apparatus is intended, deformation of the thermo-sensitive element will occur and will first return the permanent magnet 184 to its extreme left hand position as viewed in Fig. 3. Further deformation due to low temperature will result in movement of the threaded end of the screw 194 against a resilient abutment or spring 206 seated in a bore 208 provided by the head 54 so that, even under extremely low temperature conditions, there will be no damage to the thermo-sensitive element itself or to the members connected thereto. In the event that the adjusting screw 200 should be retracted excessively, or its abutment 198 damaged in any way, it will be noted, that the head 196 of the screw 194 will engage the end of the boss 202 as the temperature conditions increase, thus assuring that safe temperature conditions cannot be exceeded.

In assembling the apparatus on a portion of the skirt or mounting plate of a heater, it may be desirable to have a second point of attachment, for which purpose a bolt 210 can be threaded into the lower portion of the valve casing 38 and can receive a pair of nuts 212 which can be adjusted into contact with opposite sides of the skirt or cover plate in substantially vertical alignment with the flange 36 and nut 34 carried by the orifice spud 28.

Whereas only one embodiment of the present invention has been illustrated for purposes of providing a complete understanding of the invention, variations will occur to those skilled in the art just as they have occurred already to the present inventor, and accordingly, the invention should not be restricted to this single form beyond the scope of the appended claims.

I claim:

1. Fluid heater control apparatus comprising a valve casing, a diaphragm dividing said casing into two chambers; fuel inlet and outlet tubes having ports communicating with the first of said chambers; a valve connected with said diaphragm for registry with one of said ports, means interconnected with one of said tubes defining a pilot fuel passage, means defining a bleed fuel passage communicating with the second of said chambers for controlling said diaphragm and valve, a control valve interposed in said pilot fuel passage, and an operator comprising a rod having an end movable to a position engaging and opening said control valve, said rod having a portion accessible externally of said casing for manual operation and having an intermediate portion simultaneously projecting into and closing said bleed fuel passage.

2. Fluid heater control apparatus comprising a valve casing, a diaphragm dividing said casing into two chambers; fuel inlet and outlet tubes having ports communicating with the first of said chambers; a valve connected with said diaphragm for registry with one of said ports, means interconnected with one of said tubes defining a pilot fuel passage, means defining a bleed fuel passage communicating with the second of said chambers for controlling said diaphragm and valve, a control valve interposed in said pilot fuel passage, an operator comprising a unitary rod having an end movable to a position engaging and opening said control valve, said rod having an intermediate portion simultaneously projecting into and closing said bleed fuel passage, and means biasing said operator towards a position opening said bleed fuel passage.

3. Fluid heater control apparatus comprising a valve casing, a diaphragm dividing said casing into two chambers; fuel inlet and outlet tubes having ports communicating with the first of said chambers; a valve connected with said diaphragm for registry with one of said ports, means interconnected with one of said tubes defining a pilot fuel passage, means defining a bleed fuel passage communicating with the second of said chambers for controlling said diaphragm and valve, a magnetically actuated control valve interposed in said pilot fuel passage, a condition responsive member movable in a path adjacent said control valve, a magnet carried by said member for shifting said control valve, and valve means carried by said casing interposed between said fuel inlet tube and said first chamber.

4. Fluid heater control apparatus comprising a valve casing, a diaphragm dividing said casing into two chambers; fuel inlet and outlet tubes having ports communicating with the first of said chambers; a valve connected with said diaphragm for registry with one of said ports, means interconnected with one of said tubes defining a pilot fuel passage, means defining a bleed fuel passage communicating with the second of said chambers for controlling said diaphragm and valve, and a selecting valve carried by said casing interposed between said inlet tube on the one hand and said first chamber and passages on the other.

5. Fluid heater control apparatus comprising a valve casing, a diaphragm dividing said casing into two chambers; fuel inlet and outlet tubes having ports communicating with the first of said chambers; a valve connected with said diaphragm for registry with one of said ports, means interconnected with one of said tubes defining

a pilot fuel passage, means defining a bleed fuel passage communicating with the second of said chambers for controlling said diaphragm and valve, a magnetically actuated control valve interposed in one of said passages, a condition responsive member movable in a path adjacent said control valve, a magnet carried by said member for shifting said control valve, and a rotary selecting valve carried by said casing between said inlet tube on the one hand and said first chamber and passages on the other for selectively supplying fuel to either said first chamber or passages or both.

6. Fluid heater control apparatus comprising a valve casing, a diaphragm dividing said casing into two chambers; fuel inlet and outlet tubes having ports communicating with the first of said chambers; a valve connected with said diaphragm for registry with one of said ports, means interconnected with one of said tubes defining a pilot fuel passage, means defining a bleed fuel passage communicating with the second of said chambers for controlling said diaphragm and valve, a control valve interposed in said bleed fuel passage, a thermo-responsive element remotely spaced from said control valve, an arm secured to said element, said arm having a remote end movable through an arcuate path adjacent said control valve, and magnetic means establishing a coupling between said arm and control valve.

7. Fluid heater control apparatus comprising a valve casing, a diaphragm dividing said casing into two chambers; fuel inlet and outlet tubes having ports communicating with the first of said chambers; a valve connected with said diaphragm for registry with one of said ports, means interconnected with one of said tubes defining a pilot fuel passage, means defining a bleed fuel passage communicating with the second of said chambers for controlling said diaphragm and

30

40

valve, a control valve interposed in said bleed fuel passage, a thermo-responsive element remotely spaced from said control valve, a pendulous arm secured to said element, said arm having a remote end movable through an arcuate path in a vertical plane adjacent said control valve, and magnetic means establishing a coupling between said arm and control valve.

8. Fluid heater control apparatus comprising 10 a valve casing, a diaphragm dividing said casing into two chambers; fuel inlet and outlet tubes having ports communicating with the first of said chambers; a valve connected with said diaphragm for registry with one of said ports, means interconnected with one of said tubes defining a pilot fuel passage, means defining a bleed fuel passage communicating with the second of said chambers for controlling said diaphragm and valve, a control valve having a chamber inclined to the vertical interposed in said pilot fuel passage, a shoulder in a lower portion of said chamber defining a substantially linear valve seat, a ball received in said chamber for cooperation with said seat, said ball having a radius exceeding the width of said shoulder, and magnetic means for holding said ball away from said seat.
